ABSTRACT: A self-contained mechanism comprising a plurality of translatable mounted operation control slides is attachable to one of the side frames of a calculating machine in juxtaposition with the key stems of a plurality of operation control keys disposed in the keyboard of such machine. Upon depression of any one of these operation control keys, a cycle initiating slide is activated, and at least one control slide corresponding to the depressed key is simultaneously translated from a central inactive home position to either a forward or rearward activating position wherein selected cooperation is provided with the various mechanisms of the calculating machine to produce corresponding machine functions.

EASY DEPRESSION CONTROL MECHANISM FOR A CALCULATING MACHINE

BACKGROUND OF THE INVENTION

Calculating machines are generally provided with a plurality of live operation control keys which are depressibly arranged in predetermined column columns and rows of the calculating machine's keyboard, and which are individually cooperable with the various function producing mechanisms of the calculating machine, such keys being directly connected by linkage means to such sundry mechanisms. As a consequence of this arrangement, considerable force is commonly required in order to depress the operation control keys, such depression being hampered by the weight and drag of the various mechanisms themselves. As an additional consequence of this arrangement, serious limitations are presented to the convenient adaptation of the calculating machine, on the user's premises, to changing applicational needs, wherein it may be deemed advantageous to adapt specific control keys so that they might perform functions different from those intended by the manufacturer. Accordingly, an operation control key located in a given keyboard position is generally limited to the function producing characteristics that were anticipated at the time the machine was built by the manufacturer, and changes therein are normally realizable only at near prohibitive cost and inconvenience. Specifically, such changes in the functional characteristics of one or more operation control keys generally require extensive disassembly, modification and reassembly of the various function producing mechanisms.

SUMMARY OF THE INVENTION

It is accordingly an object of the present invention to provide means whereby the operation control keys of a calculating machine may be depressed with a minimum of force and effort, and whereby the function producing characteristics of any of the operation control keys may be altered at minimum cost and inconvenience, such alteration merely involving the removal and replacement of readily accessible operation control slides.

An important aspect of the invention is the use of a plurality of function producing control slides which are mounted for two degrees of freedom on an auxiliary side frame that is readily attachable to one of the exterior side frames of a calculating machine. The upper edges of these control slides are provided with a plurality of slots the distinctive slope formations of which are effective, in response to the depression of corresponding operation control keys, to translate the control slides from a central home position to either a forward or rearward activating position. Included among the control slides is a cycle initiating slide which is activatable by the depression of each of the operation control keys, such activation being effective to lower the control slides from their upper home positions to their lower actuating positions wherein cooperation is provided as between the forwardly and rearwardly translated control slides and the corresponding function producing mechanisms of the machine.

Another aspect of the invention is the use of a pair of interconnected bellcranks and a biased cam associated therewith as a means of lowering the control slides from their upper home positions to their lower actuating positions, the interconnected bellcranks serving also as a means for mounting the control slides for their said two degrees of freedom. Still another aspect of the invention is the use of latching means associated with the cycle initiating slide, such latching means serving to latchably secure the control slides in both their upper home and lower actuating positions.

BRIEF DESCRIPTION OF THE DRAWINGS

These and other objects, aspects and advantages of the invention will be more clearly understood from the following description when read in conjunction with the accompanying drawings, in which:

FIG. 1 is an inside elevation of the preferred embodiment of the invention showing the auxiliary side frame with the interconnected bellcranks, the biased cam, and the cycle initiating slide mounted thereon, the latter slide being disposed in its upper home position;

FIG. 2 is an inside elevation of the invention showing the various parts of FIG. 1 in their activated states and with the cycle initiating slide located in its lowered position;

FIG. 3 is a top plan view of the auxiliary side frame showing the interconnected bellcranks and a pair of grooved shafts mounted thereon;

FIG. 4 is a perspective view taken from the top side showing the cycle initiating slide and four representative operation control slides mounted in their respective grooves of the grooved shafts;

FIG. 5 is an inside elevation showing a pair of operation control slides in their upper home and central positions, and showing also an operation control key in relationship with corresponding slopes formed on the upper edges thereof;

FIG. 6 is an inside elevation showing the control slides of FIG. 5 in their lowered positions, such slides having been translated in opposite directions from their central home positions; and

FIG. 7 is a detailed view showing two of the operation control slides of FIG. 4 in their disassembled states.

DETAILED DESCRIPTION OF THE INVENTION

The preferred embodiment of the invention comprises an auxiliary side frame 21 by means of which the various parts of the mechanism are operably supported, the auxiliary side frame being attachable to the right side exterior side frame of the calculating machine. The embodiment includes a pair of interconnected, rotatable bellcranks 23 and 25 which serve to support a plurality of translatable control slides such as the slides 85, 115, 117, 119 and 121 shown in the drawings. The bellcranks 23 and 25 are rotatably mounted on the auxiliary side frame 21 by means of a pair of studs 27 which are fixed to the respective bellcranks and which extend therefrom through a pair of bushings 28 into journaled termination in the side frame 21.

The bellcranks 23 and 25 are pivotally connected at their lowermost extremities by a link 29. A spring 79 connected at one end to a stud 81 fixed to the side frame 21 and at the other end to a stud 83 fixed to the bellcrank 23, serves to bias the bellcranks 23 and 25 in a clockwise direction (as viewed in the drawings) on their respective studs 27. The bellcrank 25 is provided with a roller 55 supported by an extended stud 57 fixed to the bellcrank 25 and extending in the direction of the side frame 21. Rotatably mounted on the auxiliary side frame 21 also is a latch 59, a cam 35, and an arm 41, the latter cam and arm being connected by a link 43 pivotally supported by a stud 45 fixed to the arm 41 and a screw stud 47 secured to the cam 35. The latch 59 is rotatably mounted on the side frame 21 by means of a stud 60 and comprises an offset lug 61 formed on its lowermost portion and an extension 63 (FIG. 3) which is disposed in cooperating relationship with the extension of the extended stud 57 adjacent the roller 55 supported thereby. The cam 35 is rotatably mounted on the side frame 21 by means of a stud 37 fixed to the cam 35 and extending through a bushing 39 into journaled termination in the side frame, the location of the cam 35 being such that a raised portion thereof is disposed in cooperable relationship with the roller 55 of the bellcrank 25. The cam 35 is provided with a notch 51, and a cutout 53 the purpose of which is described in a subsequent paragraph. The rotatable arm 41 is mounted on the auxiliary side frame 21 by means of stud 42 which is fixed to the arm 41 and extends through a bushing 44 into journaled termination in the auxiliary side frame. The arm 41 is provided with a roller 49 the function of which is hereinafter described. The latch 59 is biased in a clockwise direction on the stud 60 by a spring 71 connected to a stud 75 fixed to the side frame 21 and to a stud 73 fixed to the latch 59, such clockwise bias

70 to the arm 41 and extends through a bushing 44 into journaled termination in the auxiliary side frame. The arm 41 is provided with a roller 49 the function of which is hereinafter described. The latch 59 is biased in a clockwise direction on the stud 60 by a spring 71 connected to a stud 75 fixed to the side frame 21 and to a stud 73 fixed to the latch 59, such clockwise bias

serving to urge the lug 61 into cooperating relationship with the cam 35 and more particularly with the notch 51 formed therein. The cam 35 is biased in a clockwise direction on the stud 37 by a spring 65 connected to a limit stud 69 fixed to the side frame and to a stud 67 fixed to the side surface of the cam, such bias serving to rotationally urge the cam 35 in such manner that its raised portion would upwardly activate the roller 55 supported by the bellcrank 25 and would thereby rotate the bellcranks 25 and 23 in a counterclockwise direction on their respective studs 27.

Each of the bellcranks 23 and 25 is provided with a grooved shaft 31 as best shown in FIG. 3, such grooved shafts being so disposed on their respective bellcranks that the clockwise rotation of the bellcranks by the spring 79 results in the elevation of the shafts, and the counterclockwise rotation of the bellcranks by the spring 65 and the cam 35 results in the lowering of such shafts. It will be observed from FIG. 3 that each of the grooved shafts of the embodiment is provided with 12 grooves 33 (FIG. 3), such grooves forming 12 parallel pairs of coplanar grooves. Each of these pairs of grooves is designed to accommodate a separate slide, as suggested by FIG. 4.

As shown in FIGS. 1 and 2, a cycle initiating slide 85 is disposed in the first pair of grooves adjacent the bellcranks 23 and 25, such slide being translatable carried by the slideable cooperation of a pair of slots 89 formed in the slide and said first pair of grooves 33. An enlarged circular portion of each of the slots 89 serves to facilitate the assembly of the slide on the shaft 31. This cycle initiating slide is provided with a plurality of slots formed in its uppermost portion, such slots being formed in part by angular slopes 87 which are cammingly responsive to the depression of the various operation control keys to translate the slide a minimal distance in a rearward direction (as viewed in the drawings). As indicated by FIG. 5, each operation control key is provided with an elongated key stem 86 that transverses all of the control slides that may be mounted on the grooved shafts 31. The elongated key stem 86 of each of the operation control keys is accordingly transversely aligned with a corresponding slope 87 of the cycle initiating slide 85 and is therefore effective for rearwardly activating the slide 85 against the bias of a spring 77 connected to an aperture formed in the rightmost extremity of the slide (as viewed in FIGS. 1 and 2) and to the stud 60. The cycle initiating slide 85 is also provided with a cutout 91, a slide latch 95, and a pivot pawl 107. The cutout 91 affords free activation of the slide 85 without interference from an aligning bar 93 which is rigidly connected to the auxiliary side frame 21 and to the side frame of the calculating machine, the purpose of the aligning bar being described in a subsequent section. The slide latch 95 is translatable mounted on the cycle initiating slide 85 by means of a pair of shouldered studs 97 in cooperation with a slot formed in the latch, the latter having a latch portion 103 disposed in cooperating relationship with a square stud 105 fixed to the auxiliary side frame 21. A spring 101 connected to a depending lug of the slide latch 95 and to an aperture formed in the cycle initiating slide serves to bias the slide latch 95 and the latch portion 103 in a rightward direction (as viewed in drawings) on the cycle initiating slide 85. The pivot pawl 107 is rotatably mounted by a shouldered stud 109, the rotation of the pivot pawl thereon being defined by the cooperation of a limit stud 111 fixed to the slide 85 and the extremities of a slot formed in the pivot pawl. A spring 113 is connected to an aperture formed in the pivot pawl and to a stud 114 fixed to the slide 85.

The previously mentioned 12 pairs of grooves of the grooved shafts 31 of the preferred embodiment provide for the accommodation of the cycle initiating slide 85 and 11 operation control slides. Four representative slides of the possible 11 control slides are shown in FIGS. 4 through 7 and identified by reference numbers 115, 117, 119 and 121. These representative control slides are disposed in the twelfth, eleventh, eighth, and fifth pairs of grooves 33 of the shafts 31, respectively. It will be observed that each of these four representative control slides is also provided with a pair of

slots 89, and that each is provided with a cutout 123 having a pair of prongs 125 depending thereinto, such prongs forming three slots which are differentially engageable with the aligning bar 93 when the slides are lowered from their upper home positions to their lower actuated positions, as described in greater detail in the following section.

OPERATION OF THE CONTROL MECHANISM

When a calculating machine comprising the preferred embodiment of the invention is at rest, the cycle initiating slide 85 and the various operation control slides translatable supported by the grooved shafts 31 are located in an elevated position wherein the inclined camming slopes 87 of the various slides are disposed in contiguous relationship with the elongated key stems 86 of the various operation control keys, such elevated positioning of the slides being effectuated as follows:

1. The cycle initiating slide 85 is held in its forward position (rightmost position as viewed in the drawings) by the spring 77.

2. The latch portion 103 of the slide latch 95 is disposed in latchable contact with the uppermost surface of the square stud 105, the slide latch being held in its forward position on the cycle initiating slide 85 by the spring 101. This latched positioning of the slide latch is effective to retain the bellcranks 23 and 25 in their clockwise rocked positions on their studs 27 (as viewed in the drawings), the roller 55 of the bellcrank 25 serving to blockably limit the clockwise rotation of the cam 35 by means of its blocking contact with an arcuate portion thereof formed by the cutout 53, and the extension of the extended stud 57 serving to hold the latch 59 in a slightly counterclockwise rocked position on the stud 60 by means of its contact with the extension 63. The cam 35 is held in its counterclockwise rocked position against the bias of the spring 65 by the blocking contact of the roller 55. The various parts of the embodiment are accordingly positioned as illustrated in FIGS. 1 and 5.

When one of the operation control keys of the calculating machine is depressed, the elongated key stem 86 of the depressed key effectively translates the cycle initiating slide 85 a minimal rearward distance (to the left as viewed in the drawings), at the same time translating one or more operation control slides in either a forward or rearward direction from their central position or positions according to the angles of the inclined camming slopes 87 that are encountered by the operation control key. The rearward translation of the cycle initiating slide serves instantaneously to effectuate the following:

1. The latch portion 103 of the slide latch 95 is rearwardly withdrawn from the upper surface of the square stud 105.

2. The cam 35 is rotated in a clockwise direction on the stud 37 by the spring 65, such clockwise rotation serving to rotate the bellcranks 23 and 25 in a counterclockwise direction on their studs 27 by the camming action of the raised portion of the cam against the roller 55 of the bellcrank 25, the counterclockwise rotation of the bellcranks being limited by contact of the lower portion of the bellcrank 25 against the limit stud 69.

3. The cycle initiating slide 85 and the various operation control slides are lowered by this counterclockwise rotation of the bellcranks to assume the position illustrated in FIGS. 2 and 6, the lowering of those control slides which were translated from their central positions to either their forward or rearward positions being effective to actuate the corresponding function producing mechanisms of the calculating machine. As the control slides are lowered, an engagement occurs as between one of the three slots formed by the prongs 125 of each control slide and the aligning bar 93, those control slides which were rearwardly translated being aligned by means of the rearmost slots, those slides which were translated forwardly being aligned by means of the frontmost slots, and those control slides which were not translated from their central positions being aligned by means of the central slots.

4. Upon completion of the counterclockwise rotation of the bellcranks 23 and 25, the slide latch 95 is activated forwardly by the springs 77 and 101 such that the latch portion 103 assumes a blocking contact with the lower surface of the square stud 105, the various control slides being thereby retained in actuating relationship with their corresponding function producing mechanisms throughout the cycling of the calculating machine.

As the calculating machine cycles to produce the selected machine functions, the embodiment of the invention is restored to its normal home state in the following sequence and manner:

1. Early in the machine cycle, a cam associated with the drive shaft of the calculating machine cooperates with the roller 49 of the arm 41 to thereby rotate the arm in a counterclockwise direction on its stud 42, and to rotate the cam 35 in a counterclockwise direction by means of the link 43, such counterclockwise rotation of the cam serving to extendably power the spring 65. This counterclockwise rotation of the cam 35 is sufficient to permit the offset lug 61 of the latch 59 to assume a blocking position relative to the notch 51, as motivated by the spring 71.

2. Late in the machine cycle, a separate cam of the drive shaft of the calculating machine forcibly contacts the pivot pawl 107 and thereby translates the cycle initiating slide 85 a minimal distance in a rearward direction (to the left as viewed in the drawings), such translation serving to withdraw the latch portion 103 of the latch 95 from the lower surface of the square stud 105.

3. As the cycle initiating slide 85 is released, the spring 79 rotates the bellcranks 23 and 25 in a clockwise direction on the studs 27, such rotation serving to elevate the grooved shafts 31 and the various slides to their upper home positions wherein their inclined camming slopes 87 are again disposed in contiguous relationship with the key stems of the operation control keys. As the bellcrank 25 is so rotated, the extended stud 57 contacts the extension 63 of the latch 59 to thereby unlatch the offset lug 61 from the notch 51 of the cam 35. The latter cam is accordingly permitted a minimal clockwise rotation whereby its raised portion comes into limiting contact with the roller 55.

4. When the cycle initiating slide 85 is elevated to its upper home position, it is thereupon translated to its forward position on the grooved shafts 31 by the spring 77, and the latch portion 103 of the slide latch 95 is restored to blocking contact with the upper surface of the square stud 105, the slide 85 and the various operation control slides being thereby conditioned for a subsequent depression of an operation control key to initiate a succeeding function producing cycle of the calculating machine.

Whereas the cycle initiating slide 85 is translated to its forward position upon the completion of each machine cycle, the various operation control slides (such as slides 115, 117, 119 and 121) are permitted to remain in their forwardly or rearwardly translated positions upon such cycle completion, inasmuch as these latter control slides are floatingly disposed in their respective pairs of grooves of the shafts 31. Since the elongated key stems 86 transverse all of the control slides, a given control slide which was translatable activated during the preceding function producing operation is either translatable reactivated or restored to its central position upon the depression of an operation control key to initiate a succeeding function producing operation, such translatable reactivation involving either the translation of previously activated control slides to their opposite activating positions, or in assuring that such slides remain in their previous translatable activated positions.

As an example of the types of operations that may be performed by the function producing mechanisms when forwardly or rearwardly translated control slides are lowered to their actuating positions, a brief description is herein set forth regarding the functions and purpose of the control slide 119 shown in FIGS. 4 and 7. This control slide is particularly adapted to the actuating requirements of a two-direction carry

5 accumulator of a type contained in the calculating machine for which the preferred embodiment of the invention was developed. This accumulator is comprised of a single set of accumulating gear wheels which are both additively and subtractively rotated in the performance of add and subtract operations. A plurality of carry sectors contained in this accumulator may be reversibly biased in either an add or a subtract direction in response to the depression of selected operation control keys of the keyboard. Accordingly, when an add operation control key is depressed, the cycle initiating slide 85 is translated a minimal distance in a rearward direction (as described in the foregoing), and the control slide 119 is translated to its forward activating position wherein its lowering will serve to bias the carry sectors in an add direction and the accumulating gear wheels will be rockably engaged with actuating racks after the latter racks have been differentially elevated according to the numerical values indexed in the keyboard, the return restoration of the actuating racks serving to rotate the accumulating gear wheels a corresponding distance in an add direction. On the other hand, when a subtract operation control key is depressed, the control slide 119 is translated to its rearward activating position wherein its lowering will serve to bias the carry sectors in a subtract direction and the accumulating gear wheels will be rockably engaged with the actuating racks prior to the time the latter racks are differentially elevated according to the indexed values, the differential elevation of the actuating racks in such case serving to rotate the accumulating gear wheels a corresponding distance in a subtract direction. When an operation control key other than an add or a subtract key is depressed, the control slide 119 is permitted to remain in its central position wherein its lowering will have no effect on the accumulator, neither on the biasing of the carry sectors nor on the engagement of the gear wheels with the actuating racks.

While one embodiment of the invention has been shown and described, it will be apparent that other adaptations and modifications can be made without departing from the true spirit and scope of the invention.

We claim:

1. In a calculating machine having cycling means, a plurality of function producing mechanisms; and a plurality of cycle-initiating operation control keys disposed in the keyboard thereof, a control mechanism responsive to the depression of individual ones of said operation control keys and effective for selectively activating at least one of said function producing mechanisms corresponding thereto, said control mechanism comprising:
  - a support means attachable to said calculating machine;
  - a translatable mounted and unidirectionally biased cycle initiating slide responsive activatorily to the depression of each of said plurality of operation control keys;
  - a plurality of translatable mounted operation control slides, each of said slides being translatable from a central inactive position to a first and a second activating position; and
  - means responsive to said activation of said cycle initiating slide and effective for actuating said plurality of operation control slides, said actuation of said control slides which have been translated from their said central positions to their said first or said second activating positions serving to establish operable cooperation with said corresponding function producing mechanisms of said calculating machine and to thereby produce machine functions corresponding to said individually depressed operation control keys.

2. The control mechanism defined in claim 1 wherein said translatable mounting of said cycle initiating slide and said plurality of operation control slides is provided by means of:
  - a pair of spaced-apart slots longitudinally formed in said cycle initiating slide and in each of said operation control slides;
  - a pair of spaced-apart, coplanar and interconnected bellcranks rotatably supported by said support means; and

c. a pair of spaced-apart, coplanar grooved shafts fixed to corresponding side surfaces of said pair of bellcranks, each of said grooved shafts being fixed to its respective bellcrank at a corresponding equidistant spaced-apart point from the point of rotation of said bellcrank, each of said shafts having a corresponding plurality of grooves formed therein, the axially disposed grooves of said shafts forming parallel pairs of coplanar grooves into which the walls of said slots of said slides are translatable fitted.

3. The control mechanism defined in claim 2 wherein said unidirectional bias of said cycle initiating slide is provided by means of a first spring connected to a first aperture formed in said slide and to a stud fixed to said support means.

4. The control mechanism defined in claim 3 wherein said cycle initiating slide additionally comprises:

- a. a predetermined number of vertical slots formed in the upper edge thereof, said predetermined number corresponding to the number of said operation control keys disposed in said keyboard of said calculating machine, each of said slots having an inclined rear wall for cammably receiving the key stem of its corresponding operation control key and for thereby translating said slide a minimal distance in a direction opposite its said unidirectional bias;
- b. a slotted first latch slideably mounted on said cycle initiating slide by means of a pair of spaced-apart shouldered studs housed within said slot thereof and fixed to a side surface of said slide, said first latch having a latch portion extending outwardly therefrom and being biased in the direction of said latch portion;
- c. a second aperture formed in said cycle initiating slide, and
- d. a rotatably biased pivot pawl carried by a stud fixed to said cycle initiating slide, said pivot pawl being cammably responsive to said cycling means for translating said slide a minimal distance in said direction opposite said unidirectional bias thereof.

5. The control mechanism defined in claim 4 wherein each of said plurality of operation control slides comprises:

- a. a predetermined number of differentially arranged inclined camming surfaces disposed in nonsymmetrical sawtooth fashion on the upper edge thereof, said camming surfaces being responsive to the depression of corresponding ones of said operation control keys to translate said slide from its said central position to its said first and said second activating positions;
- b. an aperture formed in said slide in associated relationship with said second aperture formed in said cycle initiating slide, said aperture having a first, second and third slot formed by a pair of spaced-apart prongs depending from the upper wall of said aperture, said second slot being associated with and defining said central positioning of said slide and said first and said third slots being associated with and defining the positioning of said slide in its said first and said second activating positions, respectively; and
- c. a first and a second variously detailed extremity, said first extremity being so detailed as to establish said operable cooperation of said slide with its said corresponding function producing mechanism when said slide is actuated while located in its said first activating position, and said second extremity being so detailed as to establish said operable cooperation of said slide with its said corresponding function producing mechanism when said slide is actuated while located in its said second activating position.

6. The control mechanism defined in claim 5 wherein each of said plurality of operation control keys is provided with an elongated key stem that transverses said cycle initiating slide and all of said operation control slides, said elongated key stem cooperating with said inclined rear wall of a corresponding one of said vertical slots formed in said cycle initiating slide to thereby translate said slide in said direction opposite

its said unidirectional bias, and cooperating also with corresponding ones of said inclined camming surfaces of said plurality of operation control slides, said latter cooperation being effective to translate said operation control slides that are associated with said depressed operation control key to either their said first or their said second activating positions and to return said previously activated operation control slides that are disassociated from said depressed control key to their said central positions.

10. 7. The control mechanism defined in claim 6 wherein said actuation of said plurality of operation control slides is characterized by the lowering of said slides from their upper home positions, wherein their said inclined camming surfaces are disposed in contiguous cooperable relationship with said elongated key stems of said plurality of operation control keys, to their lower positions wherein those of said control slides which are located in their said first or their said second activating positions operably cooperate with their corresponding function producing mechanisms to produce machine functions corresponding to said depressed operation control keys.

15. 8. The control mechanism defined in claim 7 wherein said support means additionally comprises:

- a. a square stud fixed thereto in cooperating relationship with said latch portion of said first latch slideably mounted on said cycle initiating slide, said latch portion being blockably engageable with the uppermost or lowermost surfaces of said square stud, said square stud cooperating also with one of said sidewalls of said second aperture of said cycle initiating slide to blockably limit said unidirectional biasing effect of said first spring on said cycle initiating slide; and
- b. an aligning bar connected to said support means and to the side frame of said calculating machine, said aligning bar in cooperation with said first, said second and said third slots of said apertures formed in said operation control slides serving to define said first activating, said central inactive, and said second activating positions of said operation control slides, respectively.

20. 9. The control mechanism defined in claim 8 wherein said plurality of operation control slides are retained in their said upper home positions by the blockable contact of said latch portion of said first latch against said uppermost surface of said square stud fixed to said support means, said blockable contact being enabled by the home positioning of said cycle initiating slide as influenced and controlled by said first spring.

25. 10. The control mechanism defined in claim 8 wherein said means for actuating said plurality of operation control slides comprises:

- a. a cam having an abbreviated raised portion adjacent a cutout formed therein, said cam being rotatably mounted by means of a first stud fixed thereto and journaled within said support means;
- b. a second spring connected to a limit stud fixed to said support means and to a second stud fixed to said cam at a point radially disposed of said first stud, said second spring serving to bias said cam in a predetermined rotational direction on said first stud; and
- c. a first roller rotatably mounted by means of an extended stud fixed to a first of said pair of interconnected bellcranks in cooperating relationship with said raised portion and said cutout of said cam, said second spring being expanded to its maximum biasing power when said cycle initiating slide and said plurality of operation control slides are retainably located in their said upper home positions by said blockable contact of said latch portion of said first latch against said uppermost surface of said square stud, said first roller mounted on said first bellcrank in cooperation with said cutout of said cam serving to blockably limit said second spring against said maximum biasing power when said uppermost surface of said square stud is so engaged by said latch portion of said first latch.

11. The control mechanism defined in claim 10 wherein said actuation of said plurality of operation control slides from their said upper home positions to their said lower function producing positions, upon depression of one of said operation control keys, is characterized by:

- a. said minimal translation of said cycle initiating slide in said direction opposite its said unidirectional bias, said translation being effectuated by said camming action of said elongated key stem of said depressed operation control key;
- b. the withdrawal of said latch portion of said first latch from said uppermost surface of said square stud fixed to said support means, said withdrawal resulting from said translation of said cycle initiating slide;
- c. the rotation of said pair of interconnected bellcranks to thereby lower said pair of grooved shafts supporting said cycle initiating slide and said operation control slides, said rotation of said bellcranks being motivated by the rotation of said cam by said second spring and by the camming effect of said raised portion of said cam against said first roller of said first bellcrank, said biased rotation of said bellcranks being limited by the contact of said first bellcrank's lower extremity against said limit stud fixed to said support means, said lowering of said operation control slides being effective to engage said translatably selected slots formed in said apertures of said control slides with said aligning bar supported by said support means and said side frame of said calculating machine; and
- d. the translation of said cycle initiating slide in said direction of its said unidirectional bias by said first spring, said translation being effective to latchably engage said latch portion of said first latch with said lowermost surface of said square stud, said engagement serving to retain said operation control slides in their said lower positions for one complete cycle of said calculating machine.

12. The control mechanism defined in claim 11 wherein said second spring is restored to its said maximum biasing power relative to said cam early in said complete cycling of said calculating machine, and wherein said cycle initiating slide and said operation control slides are restored from their lower positions to their upper home positions late in said complete cycling, said former restoration being effectuated by said cycling means in cooperation with cam restoring means, and said latter restoration being effectuated by said cycling

means in cooperation with said pivot pawl rotatably carried by said cycle initiating slide and by bellcrank restoring means.

13. The control mechanism defined in claim 12 wherein said cam restoring means comprises:

- 5 a. a rotatable arm supported by said support means, said arm having a second roller mounted thereon in cooperating relationship with said cycling means;
- b. a link pivotally connecting said rotatable arm and said cam, said latter connection being at a radially disposed point directly opposite said abbreviated raised portion of said cam;
- c. a notch formed in said cam; and
- d. a biased second latch rotatably mounted on said support means, said second latch having an extension arm, and an offset lug disposed in cooperable relationship with said notch formed in said cam, said cycling means in cooperation with said second roller being effective early in said complete cycling to activate said rotatable arm and said link and to thereby rotate said cam in a restorative direction and into a latched relationship with said offset lug of said second latch, said restorative rotation of said cam being effective to expand said second spring to its said maximum biasing power.

14. The control mechanism defined in claim 13 wherein

- 25 said bellcrank restoring means comprises a third spring connected to said support means and to a second of said pair of interconnected bellcranks, said third spring being effective, in response to the withdrawal of said latch portion of said first latch from said lowermost surface of said square stud by said cooperation of said cycling means and said pivot pawl carried by said cycle initiating slide, to restorably rotate said pair of interconnected bellcranks and to thereby return said pair of grooved shafts and said slides to their normal home positions, said restorable rotation of said first bellcrank, through the contact of said extended stud supporting said first roller with said extension arm of said second latch, being effective to unlatch said cam from said offset lug of said second latch and to return said first roller to its said blocking contact with said cutout of said cam, the completion of said return of said pair of grooved shafts and said slides to their said upper home positions being characterized by the translation of said cycle initiating slide in the direction of its said unidirectional bias as influenced by said first spring, and by the latchable engagement of said latch portion of said first latch with said uppermost surface of said square stud.
